DESIGN FOR A CIGARETTE ROLLER

Edgar R. Herzog, Seattle, Wash.

Application April 28, 1945, Serial No. 119,301

Term of patent 14 years

(Cl. D85—7)

To all whom it may concern:

Be it known that Edgar R. Herzog, a citizen of the United States, residing at Seattle, King County, Washington, has invented a new, original, and ornamental Design for a Cigarette Roller, of which the following is a specification, reference being had to the accompanying drawing, forming a part thereof, in which:

I claim:

The ornamental design for a cigarette roller, as shown.

EDGAR R. HERZOG.
